UNITED STATES PATENT OFFICE.

FRANCIS G. GALE, OF WATERVILLE, QUEBEC, CANADA.

MATTRESS-FRAME.

1,210,633.

Specification of Letters Patent. Patented Jan. 2, 1917.

Application filed July 13, 1914. Serial No. 850,561.

To all whom it may concern:

Be it known that I, FRANCIS G. GALE, a subject of the King of Great Britain, residing at Waterville, Province of Quebec, 5 Dominion of Canada, have invented an Improvement in Mattress-Frames, of which the following description, in connection with the accompanying drawing, is a specification, like characters on the drawing representing like parts.

This invention relates to bed bottoms and has for its object to provide a novel construction by which the bed bottom is stiffened and prevented from warping or 15 racking and by which the fabric can be tightened if it begins to sag after use.

In order to give an understanding of the invention I have illustrated herein a selected embodiment thereof which will now 20 be described, after which the novel features will be pointed out in the appended claims.

In the drawings Figure 1 is a view partly in section of one corner of the bed bottom; Fig. 2 is a section on substantially the line

25 $x-x$, Fig. 1.

I have not deemed it necessary to illustrate herein a complete bed bottom, but have shown the construction at one corner only, it being understood that this construction is duplicated at the other corners thereof.

1 is the side rail of the bed bottom or mattress frame.

2 represents the wire fabric which is connected by means of springs 3 with the end rail 4.

Each side rail 1 is provided at each end with a riser or head 5 to which the end rail is secured.

40 My invention aims to provide a novel construction for connecting the end rail 4 to the risers 5 which not only enables the fabric 2 to be adjusted to take up any slack or sag therein, but which also prevents the mattress frame from twisting or warping 45 as iron frames frequently do.

Each riser 5 is provided with a flat supporting surface 6 on which the end rail 4 rests, said end rail having an angle-iron 50 shape. Said end rail is provided at each end with a guiding and stiffening member 7 also having an angle-iron shape, the vertical leg 8 of which sets inside of and is rigidly secured to the vertical leg 9 of the end rail 4 by suitable means, such as rivets 55 10, and the horizontal leg 11 of which rests

on the supporting surface 6. Each of these guiding members 7 is provided with a guiding stud 12 which extends through a slot 13 formed in the portion 6 of the riser 5. 60 These guiding pins 12 are preferably in the form of bolts having heads 120 which rest on the horizontal leg 11 of the stiffening member 7, said bolts having screw-threaded thereto nuts 14 which engage the underside 65 of the portion 6 of the risers and serve to keep the stiffening members 7 in proper position. Each riser 5 is also provided with a vertically-extending flange 15 through which loosely passes an adjusting bolt 16 70 that extends through the vertical legs 8 and 9 of the angle-iron members 7 and 4, respectively, and has screw-threaded engagement with a nut 17 which rests against the inner face of the leg 8. This nut will be 75 non-circular and is of a size to fit between the head 120 of the bolt 12 and the horizontal leg of the angle-iron 4, said nut being held from turning by its engagement with these parts.

By means of this construction the bed bottom fabric 2 can be tightened by simply turning the bolts 16, the slots 13 providing for the adjusting movement of the end rail 4. The presence of the guiding and stiffening members 7 at the ends of the end rail 85 serves to hold the latter in proper position on the portions 6 of the risers 5 and prevent the frame from warping or becoming twisted. The supporting surfaces 6 of the 90 risers are comparatively wide and furnish a firm support for the horizontal legs 11 of the guiding members 7.

The construction above described is simple, inexpensive and provides a rigid mattress frame.

I claim:

1. In a mattress frame, the combination with side rails having risers at their ends, each provided with a flat supporting surface and an upturned flange at the outer end of said surface, of an angle-iron end rail to which the bed bottom fabric is connected, an angle-iron stiffening and guiding member secured to each end of the end rail 100 and having its vertical leg overlying the vertical leg of the end rail and its horizontal leg resting on the supporting surface, the portion of each riser on which the guiding member rests being provided with 105 a slot, a bolt extending through the horizontal legs of each guiding member and op-

erating in the slot in the riser, an adjusting bolt extending through the vertical flange of the riser and the vertical legs of the end rail and guiding member, and a nut on the inner face of said guiding member which is held from turning by contact with the head of the first-named bolt.

2. In a mattress frame, the combination with side rails having risers at their ends, each provided with a flat supporting surface and an upturned flange at its outer end, of an end rail to which the bed bottom fabric is connected, a guiding member secured to each end of the end rail and resting on the supporting surface, the portion of each riser on which a guiding member

rests being provided with a slot, a bolt extending through the guiding member and operating in said slot, an adjusting bolt extending through the vertical flange of the 20 riser and through the end rail, and a nut on the inner end of said adjusting bolt which engages the head of the first-named bolt.

In testimony whereof, I have signed my 25 name to this specification, in the presence of two subscribing witnesses.

F. G. GALE.
